Des. 180,130
Patented Apr. 16, 1957

180,130

PLASTIC SHEET MATERIAL

Russel Wright, New York, N. Y.

Application December 9, 1955, Serial No. 39,255

Term of patent 14 years

(Cl. D87—3)

The single figure of the drawing is a plan view of a plastic sheet material, showing one complete repeating unit of my new design.

I claim:

The ornamental design for a plastic sheet material, substantially as shown.
